SPOT-WELDING PLIERS

Arthur A. Campbell, Jr., Madison, Wis.

Application February 1, 1940, Serial No. 316,814

2 Claims. (Cl. 219—4)

This invention relates to an electrical welding tool and more particularly this invention relates to a portable electric spot-welding tool.

One object of this invention is to provide a portable spot-welding tool which may be easily and readily carried about without the necessity of moving heavy and cumbersome equipment.

Another object of this invention is to provide a portable spot-welding tool which is easily operated and is very efficient in operation.

Another object of this invention is to provide a portable welding tool which due to its unique construction and the fact that it is provided with removable electrode carrying jaws of different shapes, may be used to weld metal in otherwise inaccessible places.

A further object of this invention is to provide such a tool having a switch to control the heavy current through the electrodes, the switch operating only when the electrodes have come to rest in welding position thereby eliminating excessive arcing.

A still further object of this invention is the provision of adequate insulation between each of the parts to insure protection from dangerous shocks to the user of the tool.

Other and further objects of this invention will become readily apparent as the following description of preferred and practical embodiments of the invention proceeds.

In the drawing which accompanies and forms a part of this specification and in which like reference numerals refer to like parts throughout:

Figure 1 is an elevational view of one form of an electric spot-welding tool constructed in accordance with the concepts of the present invention;

Figure 2 is a longitudinal section through the tool, the jaws being moved to welding position;

Figure 3 is a transverse section taken on line 3—3 of Figure 1;

Figure 4 is a perspective view of another type of removable jaw;

Figure 5 is a perspective view of a differently shaped jaw.

Referring now to the drawing in detail, the spot-welding tool is shown in the form of pliers having a fixed jaw 1 and a movable jaw 2. The fixed jaw is rigidly secured to a head 3, and, integral with the jaw 1 and extending rearwardly from the head 3 is an insulated fixed handle 4. The head 3 consists of two plates 5 and 6, one on either side of the jaws and separated from the jaws by sheets of insulating material 7 and 8.

Insulated screws 9 secure the plates 5 and 6 of the head 3 to the fixed jaw and insulated handle 1 and 4, respectively.

The movable jaw 2 is pivoted to the head as at 10 and terminates at its rearward end in an arcuate toothed segment 11. An insulated movable handle 12 is pivoted to the head as at 13 and at its forward end carries an arcuate toothed segment 14 meshing with the toothed segment 11. Due to this construction, movement of the movable handle 12 toward the fixed handle 4 causes the jaws to approach one another. Each of the jaws is provided with a cutout portion 15 forming a stepped joint to receive a current conducting section 16 to which is removably secured an electrode 17 by means of screw 18. The two sections of the jaw are separated by a strip of electrical insulating material. The sections 16 of the jaws are secured to the main portion of the jaws by the bolt 19, and are readily removable so that sections of various shapes may be used for welding material having obstructions which would otherwise prevent the electrodes contacting the metal to be welded.

25 A conducting section of a jaw having a yoke 20 to permit welding in back of an obstruction is shown in Figure 4, while a similar conducting section having the electrode offset to facilitate welding within a narrow space is shown in Figure 5. Obviously these interchangeable conducting sections may be made in various shapes and sizes to weld differently shaped sections such as, for example, fenders, channel irons, car body tops, etc. The conducting sections 16 are 30 provided with binding posts 21 to which are fastened the heavy current carrying wires 22 leading from the secondary 23 of a transformer 24, the primary 25 of the transformer being connected to any suitable source of electrical current. It is, of course, apparent to those skilled in the art to which this invention pertains, that the electrodes and/or conducting sections may be made water cooled. This also helps to prevent excessive burning of the electrodes.

45 In electrical spot-welding it is highly desirable that the electrodes shall be in firm contact with the metal which is to be welded, before the current is sent through the electrodes in order to prevent arcing and consequent burning of the electrodes. To accomplish this the head plates 5 and 6 are provided with arcuate slots 26 and 27 to receive the pivot pins 13 of the movable handle 12. Springs 28 are placed in the slots and held in position upon studs 29 50 at the bottom of the slots and studs 30 on the

pivot pins 13. The springs 28 are of sufficient strength to hold the pivot pins against the top of the slots as the handles are being pressed together to close the jaws. After the jaws are firmly in contact with the metal to be welded continued pressure on the handles causes the springs to compress allowing the teeth of the movable handle 12 to rotate about the teeth of the movable jaw 2.

A binding post 31 secured to the handle 12 is provided with inwardly projecting switch actuating pin 32, insulated from the movable handle 12, and adapted to abut and move downwardly a plate 33 hinged to the switch box 34 carried by the fixed handle 4. Movement of the plate 33 causes a plunger 35 to move inwardly against the action of a spring 36. Mounted upon the plunger 35 so as to have pivotal movement in one direction is a dog 37. As the plunger 35 moves inwardly the dog 37 strikes a resilient metal contact 38 and moves it downward against a substantially rigid member 39 electrically connected to one side of a relay. When the contact 38 strikes the member 39 the outer end of the contact 38 bends downwardly allowing the dog 37 to pass by it and thus break the circuit. Actuation of this switch energizes a relay 40 which draws up its armature and closes the circuit to the electrodes. This relay may be connected to any suitable electrical outlet or may be connected to a third coil on the transformer 25. In this way a relatively weak current may be run through the switch and thereby eliminate the danger of electrical shock to the operator. As a further safeguard the handles 4 and 12 are covered with electrical insulation of some type, and all of the various pins, bolts, pivots and parts have insulated bushings and strips.

In operation the jaws of the spot-welding tool are placed over the metal to be welded and the handles pressed together. The jaws grip the metal and further movement of the handles toward each other activates the switch energizing the relay and closing the circuit to the electrodes. Continued movement of the handles breaks the relay circuit and the electrode circuit. Thus, regardless of the length of time the handles are held together, the current to the electrodes will merely be a short flash of current and this, of course, will prevent excessive burning of the electrodes. When pressure on the handles is released a spring 41 will return them to their open position. Due to the pivotal connection of the dog 37 to the plunger 35, the dog will swing back when it strikes the contact 38 on its upward stroke and will not move the contact.

It will be readily understood by those skilled in the art to which this invention pertains that the showing of the device is very diagrammatic and that the invention is capable of many refinements, for example, the wiring of the electrical circuits and the form and shape of the

spot-welding tool may take different forms than that shown and described herein. Also the mechanism shown and described herein to move the jaws 1 and 2 toward and away from each other 5 might well be changed to use a system of cams or levers, etc., and further, if so desired, both jaws may be made movable. Further, the jaws and electrodes of the device of this invention may be constructed so as to provide water cooling 10 for them. This could be done in various ways as is well known to those skilled in the art to which this invention pertains, and would be a relatively simple matter, its chief advantage would be to help prevent excessive burning away 15 of the electrodes due to the large amount of heat generated when a spot weld is made. The particular form of switch 34 shown and described in detail moreover, is not essential as it is obvious that many other types and forms of switch 20 to accomplish the same result could be used without departing from the spirit of the invention. Various other and further modifications can well be made without departing from the spirit of my invention and the scope of the appended claims.

What I claim is:

1. A portable electric spot-welding tool comprising, a head, a jaw and a handle rigidly fixed to and insulated from said head, a movable jaw pivotally connected to said head and having an arcuate toothed inner end, a movable handle carried by said head by means of a yielding pivotal connection in slots in said head, said movable handle having an arcuate toothed outer end to mesh with the teeth on the inner end of said movable jaw, and means to close a circuit through electrodes carried by said jaws after said electrodes have been brought into firm contact with the material to be welded.

2. An electric spot welding tool comprising: a head consisting of two plates having arcuate slots therein; a fixed jaw and handle rigidly secured to, and insulated from, said head; a movable jaw pivotally connected to, and insulated from, said head, said movable jaw having an arcuate toothed segment on its inner end; a movable handle pivotally connected to, and insulated from, said head, said movable handle having an arcuate toothed segment meshing with the toothed segment on said movable jaw; a current conducting section replaceably attached to each of said jaws and insulated therefrom; replaceable electrodes carried by each of said current conducting sections; springs in the arcuate slots of said head carrying the pivots of the movable handle; and a switch carried by said fixed handle and adapted to be actuated by the movement of said movable handle to allow a momentary surge of current to pass between said electrodes after said electrodes are firmly in contact with the material to be welded; all substantially as described.

ARTHUR A. CAMPBELL, JR.
